CLOTHES HANGER OR SIMILAR ARTICLE

Herbert L. Perrin, Santa Barbara, Calif., assignor to Fortner & Perrin, Inc., Glendale, Calif., a corporation of California

Application June 3, 1954, Serial No. 30,789

Term of patent 14 years

(Cl. D80—8)

FIG. 1.

FIG. 2.

To all whom it may concern:

Be it known that I, Herbert L. Perrin, a citizen of the United States, residing at 4420 Meadow Lark Lane, Santa Barbara, California, have invented a new, original, and ornamental Design for a Clothes Hanger or Similar Article, of which the following is a specification, reference being had to the accompanying drawing, forming a part hereof.

Fig. 1 is a side elevational view of a clothes hanger or similar article embodying my new design.

Fig. 2 is a top plan view.

Fig. 3 is a perspective view.

I claim:

The ornamental design for a clothes hanger or similar article, as shown.
